WINDING PACKAGE HOLDER

Winthrop L. Perry, Milford, N.H., assignor to Abbott Machine Co., Inc., Wilton, N.H., a corporation of New Hampshire

Original application Sept. 29, 1961, Ser. No. 141,884. Divided and this application July 19, 1962, Ser. No. 210,998

3 Claims. (Cl. 242—18)

This application is a division of my application Serial No. 141,884, filed September 29, 1961, and relates particularly to improvements in package holders for conical yarn packages in winding machines. The invention provides an acceleration of the taper of the conical winding package, a retraction of the package axially of the drive roll, minimizes the extent to which any skewed relation may exist between the package and drive roll, renders the relation of the package to the drive roll certain by positive mechanical connections at all stages of movement of the package holder, and accomplishes these objects by simple sturdy structure.

In the accompanying drawings:

FIG. 1 is an elevation showing a winding unit including the package holder of this invention;

FIG. 2 is a plan view showing the winding package holder; and

FIG. 3 is a plan view on a larger scale and partly in section of the cone holder of FIG. 2.

Although the winding head 60 may be provided with a grooved package-driving roll that also traverses the winding yarn to distribute it on the winding package, the preferred head shown has a roll 85 which is suitably driven, for frictionally rotating the yarn package, and a separate yarn-traversing thread guide 72 which is reciprocated by a helically grooved cam at a variable speed which is, in known manner, faster when near the tip end of the package and slower when near the base end of the package.

The winding package is received between the two arms of a generally U-shaped yoke 90. The left of these arms carries a rotatable socket 91 for the conical tip of a paper cone C, FIG. 3, the socket turning in a ball bearing 91a. Slidably mounted in a boss 92 at the end of the other arm of the yoke a shaft 93 carries a disc 94 turning on a ball bearing 94a. Disc 94 carries a rubber ring 95 engageable with the interior surface of the cone. Shaft 93 is yieldingly urged to the left by a lever 96 which is pivoted at 97 and biased by a spring 98. The disc 94 may be withdrawn from the cone to release the cone by swinging the lever 96 by its handle 96a. The handle and lever can also be used to raise and lower the cone.

For assuring a continued increase in taper of the winding package even as it approaches a large diameter, the yoke 90 is constrained to rotate around an axis that is inclined both vertically and horizontally relative to the package drive roll axis and to the line of nip between package and drive roll. The yoke 90 is clamped by extensions 99 to a rod 100 which is supported by bearings 101a and 101b in which the rod 100 can both rotate and move lengthwise. These bearings define an axis for rod 100 which is inclined to the axis of the package drive roll, the rod axis where it approaches 101a being more remote from the package drive roll axis than where the

2

rod axis approaches 101b. The amount of this inclination can readily, as in the machine illustrated, be made such that the cone axis continually increases its inclination to the drive roll axis as the package grows. The drive roll axis is indicated at 85x in FIG. 1.

Reference has been made to the rod 100 being capable of sliding in the bearings 101a and 101b. This is for the purpose of retracting the winding cone in the direction of its larger end as the winding progresses. A bracket 104 movable with the yoke 90 carries the inner element of a spherical bearing 105. A stud 106 fast on the frame of the winder head carries the inner element of another spherical bearing 108. The two other elements of the two spherical bearings are coupled by a tie-rod 109. Thus bearing 105 is constrained to move in an arc around bearing 108 as the winding package grows. As the yoke 90 rises it and its rod 100 must shift to the right in FIG. 2 and when a new empty cone is applied, and the yoke is lowered to place the cone on its drive roll the yoke is re-stored to the left.

I claim:

1. A winding machine for conical yarn packages including a package-driving roll, a yoke including means for rotatably holding the two ends of a yarn-receiving cone, means mounting the yoke for pivotal movement around an axis which is inclined both vertically and horizontally to the line of nip between package and roll so as to establish a positive relation between the rates of movement of the two ends of the cone away from the roll, and a link 25 pivoted to the yoke and to a point fixed relative to the location of the drive roll for constraining the yoke to a longitudinal shift along said inclined axis as the yoke turns around said axis.

2. A winding machine for conical yarn packages including a package-driving roll, a yoke including means for rotatably holding the two ends of a yarn-receiving cone, means mounting the yoke for pivotal movement around an axis which is inclined both vertically and horizontally to the line of nip between package and roll so as to establish a positive relation between the rates of movement of the two ends of the cone away from the roll, said mounting means including bearings spaced along said inclined axis and portions movable with said yoke and slidably and rotatably in said bearings, and a link pivoted 35 to the yoke and to a point fixed relative to the location of the drive roll for constraining the yoke to a longitudinal shift along inclined axis as the yoke turns around said axis.

3. A winding machine for conical yarn packages including a package-driving roll, a yoke including means for rotatably holding the two ends of a yarn-receiving cone, means mounting the yoke for pivotal movement around an axis which is inclined both vertically and horizontally to the line of nip between package and roll, so as to establish a positive relation between the rates of movement of the two ends of the cone away from the roll, and means for constraining the yoke to a longitudinal shift along said inclined axis as the yoke turns around said axis.
